HANDLE GUIDE

Emile Belanger, Drummondville, Quebec, Canada

Application April 18, 1944, Serial No. 531,608

3 Claims. (Cl. 29—80)

My invention relates to a handle guide for files and other such tools of the same type which require to be fixed in precise relation to the article being worked, for example, in filing the teeth of a saw.

The operator should have proper means to guide his hand and fingers so that when he is operating the tool there should be the least variance in its motion. I have devised such a guide and in using same the operator is also saved the strain on his eyes due to the fact that he need not have his sight fixed permanently on the operation to detect or divert any faulty motion.

My handle guide is relatively cheap in construction and will perform a much greater amount of work and a better quality of work in a given time.

These and other advantages will appear readily upon reading the specification together with the drawing, in which,

Figure 1 shows a side view of my improved handle guide with a file fixed in position, and

Figure 2 shows a transverse cut looking from the end of the file.

By referring to the drawing it will be seen that my invention consists in short in the provision of side positions on the handle which conform to the normal position the hand and fingers will take in operating or using a tool such as a file. The handle "A" consists of a gripping portion at the top which is rounded and of decreasing diameter towards the centre. This portion is gripped by the palm of the hand and the three fingers other than the index and thumb. Just below the narrowed centre point of the handle I provide a ridge 1 of a diameter about the size of the top of the handle. Below this ridge 1 I provide a depression 2 which has a diameter about equal to the centre narrowed portion of the handle. This is followed by a small ridge 3 which tapers out into triangular facets 4. The ridge 1 is a position or rest for the thumb and is provided on the top side with six cavities 5 of equal size to provide finger positions for fingers other than the index finger. On the other side of the ridge in the depression 2 I provide elongated cavities 6 also of equal size and six in number. These extend from the bottom side of the ridge 1 and into the top side of the smaller ridge 3. These cavities 6 are the positions for the index finger. It is important to note the relative alignment of these cavities for the thumb and index fingers. The division line between any two cavities 6 is opposite the centre of a cavity 5 in ridge 1. This alignment is made to correspond to the normal position the fingers should take on a handle when a tool is being properly operated.

As a result of these fixed positions in fixed relation on the handle the operator is assured in advance that he is holding the handle properly and need not apply constant pressure on the handle and keep his eyes fixedly on his work.

It follows also that if a period of rest or a change in his job is necessary the operator can begin to work more quickly.

The smaller ridge 3 is tapered and has three facets 4 corresponding in number to the sides of the file B and in parallel alignment with them. These facets 4 are so aligned that the division line between two facets is opposite the division line of a cavity 6 just above.

10 In the drawing I have shown a file B which is positioned in the handle A by inserting the point in the hole 7 in the centre of the bottom of the handle. It will be seen from the drawing that the alignment of the facets 4 fixes the normal relative position of the file to the handle so that the operator is assured that when he has gripped the handle his file is also properly positioned.

What I claim is:

- 20 1. A handle guide for files having a number of positions thereon to receive and fix the fingers of the operator on such handle in proper relation to the file, said positions being provided by means of a tapered palm rest portion, a series of circumferentially arranged depressions for the fingers other than the index finger of the hand of the operator, a second series of like arranged depressions to provide index finger positions, and an intermediate ridge portion between said sets of depressions to provide a thumb rest whereby when the handle is gripped, the thumb of the operator will rest on the said ridge portion, and the index finger will rest in one of the said second series of depressions.
- 25 35 2. A tool handle having a guide means for fixing the position of the hand of the operator for thereby fixing the precise relationship of the tool to the work, said handle having a socket at one end to receive and retain the tool, facets at the
- 30 40 45 50 55 60 said tool receiving end corresponding in number to the sides of the tool, a tapered ridge adjacently above said facets, a series of elongated depressions adjacently above said tapered ridge, a second tapered ridge adjacently above said depressions, a second series of depressions adjacently above said second ridge, and an elongated grip portion narrowing down in diameter to about the center point of the length of the handle to merge with the said second set of depressions and at its opposite end rounded off.
3. In combination with a file, a handle guide, said handle having two spaced sets of cavities equal in number circumferentially arranged and longitudinally extending, one set arranged above the other, and facets at the bottom end of the handle corresponding to the number of sides on the file, each facet arranged in alignment with a side of the file.

EMILE BELANGER.
